UNITED STATES PATENT OFFICE.

WILLIAM E. RHODES, OF ALHAMBRA, AND EDWIN W. POTTER, OF LOS ANGELES,
CALIFORNIA.

WATER-GRAVE.

1,105,926.

Specification of Letters Patent.

Patented Aug. 4, 1914.

Application filed March 16, 1914. Serial No. 825,166.

To all whom it may concern:

Be it known that we, WILLIAM E. RHODES, a citizen of the United States, residing at Alhambra, in the county of Los Angeles and State of California, and EDWIN W. POTTER, a citizen of the United States, residing at Los Angeles, in the county of Los Angeles and State of California, have invented a new and useful Water-Grate, of

10 which the following is a specification.

The invention relates to systems of hot water heating, and has for its principal object the provision of a water grate which has a large heating surface and which can be applied, or built in, to an ordinary gas range so that the flame of the gas range may be used for heating water and for other purposes simultaneously.

In the ordinary form of water heater 20 using a gas flame, the hot gases are allowed to escape after having heated the water, and these gases contain a considerable number of heat units. By using the means disclosed in this application, these gases may 25 be used for cooking purposes and for keeping foods, or other materials, in a warm condition.

Other objects and advantages will be evident hereinafter.

30 Referring to the drawings, which are, for illustrative purposes only, Figure 1 is a plan of a cook stove equipped with our invention. Fig. 2 is a partial sectional elevation on the plane x^2-x^2 Fig. 1. Fig. 3 is a perspective view of one form of water grate. Figs. 4 and 5 are plan views of alternative forms of grates.

In the form shown in the drawings, 1 is a water tank supplied from an external 40 source with cold water through a pipe 2 and having a hot water pipe 3 through which hot water may be drawn off. 4 is an ordinary gas range having burners 5, 6, 7 and 8 fed with gas from a pipe 9 as is

45 common practice in gas ranges. A water grate 10, consisting of a hot water head 11 and a cold water head 12, connected by suitable water legs 13, may be placed in the top of the range over the burners 5 and 6, approximately as illustrated in Fig. 1. A cold water inlet pipe 14 and a hot water outlet pipe 15 are provided communicating with the heads 12 and 11 respectively. The pipe 15 is connected by a 55 union 16 to pipes 17 and 18 and with the tank 1 near its upper end, and the cold

water pipe 14 is connected through pipes 19 and 20 with the lower end of the tank 1.

The forms illustrated in Figs. 4 and 5 consist of similar heads connected by similar pipes, but have a circular and square form for fitting into different types of stoves. The water connections in the forms shown in Figs. 4 and 5 are similar to those illustrated in Fig. 2.

The method of operation of our invention is as follows: The heater being in place as shown in the drawings, the gas in either or both of the burners 5 and 6 is lighted, and the heat therefrom, ascending, heats the water in the water legs 13, and passing upwardly may heat cooking utensils placed on the upper surface of the legs 13, these legs not only forming a heating medium but also forming a supporting medium upon which cooking utensils may be placed. This heating of the water in the legs 13 causes a circulation of water through these legs, thus supplying hot water to the tank 1 through the pipe 18 and drawing 70 colder water from the bottom of the tank 1 through the pipe 20. There is thus a continual circulation of water downwardly through the tank 1 and upwardly through the legs 13 during the time that these pipes are 75 heated by the flame. A considerable economy results from this construction on account of the fact that in ordinary cooking operations it is not generally necessary to have all of the burners going at full blast at one time, 80 and the burners 5 and 6 may be turned relatively low and yet be hot enough to supply plenty of heat for heating the water in the tank 1 and in addition keeping the contents of utensils placed thereon at a 85 moderate heat.

The water grate 10 may be permanently installed in the range, or it may be made removable and used interchangeably with a standard top.

100 Various types of water grates have been developed in which the gas burner is simultaneously used to act upon cooking utensils or the like and heat water in the grate. None of these, so far as we are aware, employ hot and cold water head connected by a plurality of water legs and none of them use these legs as the actual support for the utensils.

105 We claim as our invention:

110 1. In combination with a gas range having gas burners, a water grate comprising

a hot water head adapted to be supported by the top of said range, a cold water head below said hot water head, a series of water legs connecting said heads and projecting over the burners of said range, and pipe means for connecting each of said heads with a water tank.

2. In combination with a gas range having gas burners, a water grate comprising 10 a hot water head resting upon and supported by the top of said range, a cold water head beneath said hot water head, a series of water legs between said heads, and pipe means for connecting each of said heads 15 with a water tank, said water legs forming a supporting framework in the same plane as the top of the stove upon which cooking utensils may be placed.

3. In a water heater the combination of a cold water head, a hot water head, a plurality of water legs communicating between the cold water and hot water heads, such water legs forming a horizontal cooking utensil surface at their upper extremities and above the cold water head, means for supplying cold water to the cold water head, and means for drawing hot water from the hot water head.

In testimony whereof, we have hereunto set our hands at Los Angeles, California, 30 this 25th day of February, 1914.

WILLIAM E. RHODES.
EDWIN W. POTTER.
